UNITED STATES PATENT OFFICE.

JOHN J. EAGAN, OF SAN FRANCISCO, CALIFORNIA.

SYSTEM FOR CONDUCTING WATER AND SEWAGE THROUGH TUNNELED STREETS.

No. 908,980.

Specification of Letters Patent.

Patented Jan. 5, 1909.

Application filed August 17, 1906. Serial No. 331,054.

To all whom it may concern:

Be it known that I, JOHN J. EAGAN, a citizen of the United States, residing at San Francisco, in the county of San Francisco, State of California, have invented new and useful Improvements in Systems for Conducting Water and Sewage Through Tunneled Streets, of which the following is a specification.

10 My invention relates to improvements in systems for conducting water and sewage through tunneled streets.

The object of my invention is to provide an improved method for conducting water through tunneled streets, particularly in those containing longitudinal tunnels wherein underground street cars are operated, the tunnel being under a sidewalk in which position it may be effectively lighted by the 20 means known as "sidewalk lights", the pipes for the conveyance of water and sewage being so constructed and placed as to form an effective means for such conveyance without the piercing of the tunnel, thereby 25 removing liability to leakages into the tunnel or a decrease in its strength, at the same time carrying such pipes in proximity to the walls of the tunnel so as to effect a saving in excavation and permitting descent into the 30 sewer directly from the street instead of through the tunnel. And to said ends, my invention consists in the novel construction and arrangement of parts described and claimed in the following specification, and 35 illustrated in the accompanying drawing.

Referring to the figures of the drawing Figure 1 represents a transverse section of an underground tunnel, placed beneath one of the sidewalks, showing my construction of 40 the sewer as leading from a dwelling to the main longitudinal sewer and also my trough in the tunnel for conveying water for drinking or flushing purposes. Fig. 2 is a cross section of the tunnel showing the main sewer 45 running at right angles to the street in proximity thereto and the manhole leading to the sewer as well as the sediment basin, the manhole and sewer being partly broken away to illustrate the path of the sewage as indicated by the arrow, the manhole being shown 50 on an intersecting street between sidewalks.

In the figures A shows a main sewer pipe running in the same direction as the tunnel 2. B represents a main sewer pipe running 55 transversely to said sewer pipe A, constitut-

ing a sewer fed by the main longitudinal sewer. The sewer pipe B has a bend 3 so that the same may run directly beneath the tunnel as shown at 4 and then bend upwardly and then laterally to pipe A placed at the 60 customary distance in the body of the street. A manhole 6 placed on one side of the tunnel leads from the street directly to the sewer beneath.

5 designates a sediment basin which flares 65 outwardly to its base to more effectively hold the sediment until the sewer cleaners remove it.

The arrow in pipe B shows the course of the sewage into pipe B' conducting it from 70 such pipe B through manhole 6. The pipe 8 running from a dwelling to the main sewer pipe, has a downward bend 7 in proximity to the wall of the tunnel and thence runs laterally to the pipe A. A transverse section 75 of a railway is shown in Figs. 1 and 2. The manhole 6 is shown in Fig. 2 as surmounted by a cover for the protection of pedestrians or animals.

In case of the breaking of pipe 10, lying 80 in trough 9, for the conducting of water for drinking or flushing purposes, the water will flow in the trough 9, so that the tunnel will answer as a conductor of water as well as a passageway for the cars running on the 85 tracks therein.

By the use of my invention as shown, the ground under the pavement can be used for purposes other than the operation of an underground railway, and the tunnel is not 90 obstructed by any pipe running under the pavement or a sidewalk.

Having thus described my invention what I claim as new and desire to secure by Letters Patent, is:

1. A system for conducting water and sewage through tunneled streets consisting in combination with the tunnel having a longitudinal trough containing a pipe at one side of the base of said tunnel, a sewer pipe lying 100 transversely in close proximity to said base of the tunnel, said pipe curving upwardly at one end and thence extending laterally, a manhole at one end of said tunnel leading vertically from the sidewalk to said pipe, 105 and a downwardly flaring basin for sediment at the base of said manhole, said basin extending below said pipe, and a pipe running transversely over said tunnel and thence continuing downward vertically in prox- 110

2
imity to the other side of said tunnel and thence extending laterally to the main longitudinal sewer.

2. A system for conducting water and sewage through tunneled streets consisting in combination with the tunnel running longitudinally under a sidewalk, a sewer pipe lying transversely in close proximity to the base of the tunnel, and thence curving upwardly at one end and extending laterally, a manhole having a plurality of openings for the passage of sewage therethrough, a downwardly flaring basin for sediment at

the base of said manhole extending below said pipe, and a pipe running transversely over said tunnel and thence continuing downward vertically in proximity to the other side of said tunnel and thence extending laterally to the longitudinal sewer.

In testimony whereof I affix my signature in presence of two witnesses.

JOHN J. EAGAN.
